GASIFYING APPARATUS

Aldo Curioni, Larchmont, N. Y., assignor to The Gasolaire Corporation, New York, N. Y., a corporation of New York

Application January 17, 1933, Serial No. 652,233

12 Claims. (Cl. 261—92)

This invention relates to devices for gasifying volatile liquid fuels and more particularly refers to improvements in devices for producing combustible gas from volatile liquid fuels, adapted 5 for use in connection with ordinary gas burners, such as are found in gas stoves and like appliances.

It is obviously desirable that an apparatus of the character to which this invention refers be 10 adaptable for use in connection with a wide range of fuels, different fuels calling as a rule for different ratios in the relative quantities of air and vaporized fuel entering into the composition of the gas delivered to the pipe line. 15 Another consideration is that such an apparatus may be called upon to meet quite a wide range of operative conditions as regards the number of burners served, since in a stove one burner only may be used at one time and three or four burners at some other time. A suitable 20 regulation of the amount of gas produced may, at times, be in order, although as a rule this is unnecessary because since the burners themselves form a part of the circulating system they 25 act, in a sense, as valves regulating the flow and, therefore, the amount of gas produced.

It is also desirable that an apparatus of this kind be reduced to its utmost simplicity, in order to lower its cost of production, while increasing 30 its effectiveness by reducing the number of working parts.

The primary object of this invention is accordingly to provide a novel and improved apparatus, consisting of a relatively limited number of parts, adapted to effectively vaporize liquid 35 fuels, said apparatus having a large generating capacity in proportion to its size.

Another object is to provide, in an apparatus of the character specified, readily operable 40 means for varying at will the relative proportions of air and fuel vapor in the gas delivered to the pipe line.

A further object is to provide, in a gasifying apparatus of the type above referred to, novel 45 and improved means for comminuting the fuel and for projecting it into passages having a relatively wide evaporating surface, facilitating the rapid vaporization of said fuel by a current of air forced through said passages.

A still further object is to provide, in a gasifying 50 apparatus of the character specified, novel, simple and effective means for automatically returning the unvaporized fractions of the fuel to the zone of action of the fuel-projecting means, 55 so as to cause said unvaporized fractions to be

immediately re-routed through the vaporizing cycle and avoid the possibility of the heavier ends of the fuel being returned to the supply tank to gradually lower the quality of the fuel therein contained. 60

Other objects and advantages of the present invention will more fully appear as the description proceeds and will be set forth and claimed in the appended claims:

My invention is illustrated by way of example in the accompanying drawings, in which:

Fig. 1 is a side view in elevation of an apparatus embodying my invention, partly broken away and sectioned;

Fig. 2 is a plan view thereof with the top removed; 70

Fig. 3 is a vertical cross section through line 3—3 of Fig. 1;

Fig. 4 is a fragmentary longitudinal vertical section through line 4—4 of Fig. 3; 75

Fig. 5 is a detail front view of the fan forming part of the apparatus;

Fig. 6 is a fragmentary vertical section through line 6—6 of Fig. 2;

Fig. 7 is a fragmentary vertical section through line 7—7 of Fig. 2; and 80

Fig. 8 is a detail view in elevation, partly sectioned, illustrating a type of tank which may be used as a source of fuel supply.

Referring to said drawings, 60 designates a base upon which are mounted the gasifying apparatus 61 and the tank 62, constituting the source of liquid supply. 85

The gasifying apparatus comprises an elongated casing 63, provided with a top 64 and supported by three uprights, such as 65. The inside of the casing is divided by suitable vertical partitions into several chambers. A C-shaped chamber 66 runs along the two sides of the casing and its front end 67. The inner space delimited by the walls of said peripheral chamber is divided by a transverse partition 68 and a longitudinal partition 69 into an air-supply and heating chamber 70, a fan chamber 71 and an air-distributing chamber 72. 90

One of the ends of the C-shaped chamber 66, which I will call its inlet end, constitutes a housing 73 for an impeller or splasher wheel 74, said wheel being used for projecting the fuel in the vaporizing space or chamber, in a manner which I will later describe. 100

Housing 73 is directly alongside air-distributing chamber 72, being separated therefrom by partition 75. Said chamber 72 communicates with chamber 70 by means of openings 76, provid- 105

110

ed through partition 68, and it also communicates with impeller wheel housing 73, by means of openings 77, provided in partition 75.

Impeller wheel 74 is fixed on shaft 78 of an electric motor 79, said shaft running transversely through housing 73 and chamber 72, and projecting beyond partition 69 into chamber 71, where its free end carries a fan 80.

10 The function of said fan is to draw the combustible gas generated by the apparatus through suction conduit 31, coaxial with shaft 78 and to force it through a pipe line 82, issuing from the top 64, said pipe line leading to the place of consumption of the gas.

15 Sampson of the gas.

15 The intermediate portion of chamber 66, that is, that portion of said chamber which runs from housing 73 to housing 83 for conduit 81, at the opposite end, constitutes the vaporizing chamber of the apparatus and to this end is fractionated in

20 a number of relatively shallow superimposed sections 84, formed by C-shaped channelled sheet metal members 85, the object of the resulting cellular construction being to provide a large distributing and evaporating surface for the fuel delivered to said vaporizing chamber by the impeller wheel 74.

25

Air-supply and heating chamber 70 is provided with an inlet opening 86 and contains means for heating the air passing therethrough, said heating means being preferably constituted by electric heating elements, which may conveniently be inserted in the same circuit with motor 79. For the sake of economy and convenience, when a volatile fuel is used, such as gasoline, I prefer to employ as heating means an electric bulb, or bulbs, such as shown at 87, such a type of heating means possessing the advantages of low cost, ease of replacement, and effective prevention of the possibility of direct contact between the heating elements and the combustible gas.

The bottom of housing 73, which is somewhat lower than the bottom 88 of the casing, contains a certain quantity of liquid fuel, just enough to submerge part of the lower peripheral portion of the impeller wheel. The fuel is normally supplied to housing 73, from a supply tank, such as 62, the level of the liquid within housing 73 being automatically maintained in any suitable manner. For instance, tank 62 may be divided into an upper main supply chamber 89 and a lower auxiliary chamber 90, within which the liquid 91 is maintained at the level of the liquid within housing 73 by a float controlled valve 92. Said valve is carried by a stem 93, upwardly projecting from float 94 and is held tightly against its seat 95 when the liquid in chamber 90 reaches its normal level, as shown in Fig. 8. When the level of the liquid in chamber 90 decreases, float 94 will descend and new liquid will be admitted from chamber 89 into chamber 90 by valve 92, reestablishing the liquid within chamber 90 to its normal level.

Impeller wheel 74 is preferably made out of a sheet-metal disk, having a circumferential series of radially directed slits, such as 95 (see Fig. 4), the tongues defined by said slits being alternately twisted to one side and the other, so as to form a circumferential series of blades 96, disposed at an angle to the plane of rotation of the wheel. As stated, the lower portion of said blades is submerged in the liquid contained at the bottom of housing 73, as Fig. 4 clearly shows, so that rotation of said wheel in a clockwise direction, with respect to Fig. 4, will cause the same to act as an impeller projecting the liquid in spray or com-
75 minuted form with great force directly into the

inlet end of sections or cells 84 of the vaporizing chamber.

The portion of conduit 81 within housing 83 is provided with a segmental opening 97, completing the path to be traveled by the air admitted to chamber 70 through inlet 86. The suction exerted by the fan causes air to enter chamber 70, where it is heated by bulb 87 and to issue through openings 76 into chamber 72, thence through openings 77 into housing 73 and then to follow the cellular sections of the vaporizing chamber 66 from housing 73 to housing 83, as indicated by the arrows in Fig. 2. As the air leaves sections 84 of the vaporizing chamber, it enters conduit 81 through opening 97, and is sucked up by the fan and forced thereby through pipe line 82.

The rotation of the fan is shared by the splasher wheel, which acting as an impeller, projects the fuel particles into sections 84 of the vaporizing chamber, as explained, so that the air flowing through said vaporizing chamber from housing 73 to housing 83 carries the liquid particles throughout the length of the vaporizing chamber and effectively vaporizes the same. The vaporizing action is, of course, assisted by the velocity 100 of the air current and by the fact that the liquid will automatically become spread upon the very large surface provided by members 85. The heating of the air is, of course, a potent factor in increasing the rate of vaporization of the fuel. 105

The fuel is supplied to housing 73 by a feed line 98, which is connected at 99 to a transversal tubular connection 100, running from the pump housing 73 to the bottom of housing 83. The less volatile portion of the fuel admitted to the vaporizing chamber may not be vaporized in its entirety so that some liquid fuel may collect at the bottom of housing 83 and when this happens, said unvaporized portion of the fuel is automatically redirected by connection 100 to the zone of action of impeller wheel 74, within housing 73. Said unvaporized portions will, therefore, once more be projected through the vaporizing chamber where they will eventually be completely vaporized; so that the heavy unvaporized ends will be automatically prevented from returning to the supply tank and gradually lower the quality of the fuel therein contained. Their vaporization is, of course, assisted by the fact that their temperature had already been raised before, when passing through the vaporizing chamber.

As stated in the premises, I have found that for the apparatus to be suitable for use under all practical conditions, both as regards the quality of fuel used and the gas output, it is desirable to 130 provide means for regulating the quantity and composition of the gas delivered to the pipe line by varying more or less the quantity of air in proportion to the fuel vapor. To this end, conduit 81 is caused to project beyond the outer wall 101 of 135 housing 83, its projecting end 102 being provided with a segmental opening 103. Openings 97 and 103 are controlled by a sleeve valve 104, rotatably mounted within conduit 81, said sleeve valve being provided with and actuated by a front closure 140 105 through the intermediary of a bolt 106, provided with a projecting handle 107.

Sleeve valve 104 is provided with two segmental openings, 108, 109, adapted to register with segmental openings 97, 103, respectively, said segmental openings 108, 109 being angularly displaced with respect to each other to an extent causing one of openings 97, 103 to be fully closed by the sleeve valve when the other one is 145 150

fully open by the corresponding opening in the sleeve valve.

The drawings illustrate the sleeve valve about midway between its two extreme positions, and in 5 said position it will be seen that the gas delivered to pipe line 82 will be composed in about equal parts of the saturated gas issuing from the vaporizing chamber and fresh air admitted through opening 103 of conduit 81. If the sleeve valve is 10 rotated in a clockwise direction, with respect to Figs. 6, 7, the proportion of fresh air admitted to the mixture will gradually decrease, while the proportion of the gas issuing from the vaporizing chamber will increase; and conversely, if the 15 sleeve valve is rotated in a counterclockwise direction, a weaker mixture will be delivered to pipe line 82 through the resulting increased proportion of air.

It is thus seen that I provide an extremely simple 20 and efficient gas generating apparatus, which due to its design possesses a large generating capacity in proportion to its bulk. The apparatus also possesses a remarkable adaptability for use in connection with all type of volatile liquid fuels, 25 due to the simple arrangement of mixing or regulating valve described.

It is obvious that where very considerable variations have to be met at the consuming end, it 30 may be desirable to provide separate controls for the air and combustible mixture passages, and it is within the scope of my invention to do so.

While due to its simplicity and effective action, I prefer to use the impeller wheel type of liquid 35 atomizing and distributing means described, acting by impact and centrifugal force upon the liquid, it is within the scope of my invention to use other means for admitting to or projecting the volatile liquid fuel into the cellular sections of the vaporizing chamber. It is obvious that the 40 arrangement described is very effective, because the impeller wheel both atomizes and impels the liquid with great force into the vaporizing chamber sections; furthermore, its action is continuous instead of being intermittent, as is the case with 45 a pump, and is applied with equal effect to the heavy as well as the light fractions of the fuel. On the other hand, the effectiveness of the device is not solely due to the manner in which the liquid is directed into the vaporizing chamber, 50 but also to the special construction of the vaporizing chamber itself; and effective vaporization will, therefore, also be had if an atomizing means other than that shown and described is employed.

It is to be noted that in the embodiment illustrated the action of the fan, which is mounted at the delivery end of the vaporizing chamber, is to create a depression in the vaporizing chamber, whereas in other devices heretofore known the fan was mounted at the inlet end of the vaporizing 55 chamber, creating a certain pressure therein. This results in a further remarkable increase in the vaporizing efficiency of the apparatus.

The inventive idea may be carried into practice 60 in ways different from that shown; the drawings will, therefore, be understood as being intended for illustrative purposes only and not in a limiting sense. I, accordingly, reserve the right to carry my invention into practice in all those ways 65 and manners which may enter, fairly, into the scope of the appended claims.

I claim:

1. In a vaporizing device comprising a vaporizing 70 chamber, means to direct liquid to said chamber to be vaporized, and a source of liquid serving

said directing means, means forming an integral part of the device for supplying a current of air through said chamber, means for admitting outside air to said air current supply means, to be mixed with the gaseous mixture issuing from the vaporizing chamber, and adjustable means for regulating the relative amounts of air and gaseous mixture entering in the composition of the gas generated by the device, said adjustable means providing a constant volume of combined air and gaseous mixture. 80

2. In a vaporizing device comprising a vaporizing chamber, means to direct liquid to said chamber to be vaporized, and a source of liquid serving 85 said directing means, a port at the outlet end of said chamber, a suction fan creating a suction within said chamber through said port and drawing air therethrough, an additional port admitting outside air to the suction end of said fan, and adjustable valve means controlling said ports, and arranged to increase the opening of one of said ports while decreasing the opening of the other of said ports. 90

3. In a vaporizing device of the character described, a vaporizing chamber of cellular formation having a plurality of vertically spaced substantially imperforate partitions, each adapted to collect and retain liquid spread in a thin film, said partitions forming a plurality of relatively long narrow passages providing relatively long 100 paths of travel for said liquid and also providing a relatively large evaporating surface, means for projecting liquid into said passages, and means directing a current of air through said passages. 105

4. In a vaporizing device of the character described, a vaporizing chamber consisting of a plurality of superimposed relatively long, narrow and shallow substantially horizontal sections, a supply of liquid in front of said chamber, and an impeller wheel partly submerged in said liquid, 110 atomizing and directing said liquid to said sections, by centrifugal action. 115

5. In a vaporizing device of the character described, a vaporizing chamber consisting of a plurality of superimposed relatively long, narrow and shallow substantially horizontal sections, a supply of liquid in front of said chamber, an impeller wheel partly submerged in said liquid, 120 atomizing and directing said liquid to said sections, by centrifugal action, and means for redirecting to said liquid supply liquid unvaporized within said chamber. 125

6. In a vaporizing device of the character described, a vaporizing chamber consisting of a plurality of superimposed relatively long, narrow and shallow substantially horizontal sections, a supply of liquid in front of said chamber, an impeller wheel partly submerged in said liquid, atomizing and directing said liquid to said sections, by centrifugal action, means for redirecting to said liquid supply liquid unvaporized 130 within said chamber, and means for creating a current of air through said chamber. 135

7. In a vaporizing device of the character described, a vaporizing chamber consisting of a plurality of superimposed relatively long, narrow and shallow sections, a supply of liquid in front of said chamber, an impeller wheel partly submerged in said liquid, atomizing and directing said liquid to said sections, by centrifugal action, means for redirecting to said liquid supply liquid unvaporized 140 within said chamber, a fan for creating a current of air through said chamber, and a shaft carrying both said impeller wheel and fan. 145

8. In a vaporizing device of the character de- 150

- scribed, a vaporizing chamber consisting of a plurality of superimposed relatively long, narrow and shallow sections, a supply of liquid in front of said chamber, an impeller wheel partly submerged in said liquid, atomizing and directing said liquid to said sections, by centrifugal action, means for redirecting to said liquid supply liquid unvaporized within said chamber, means for creating a current of air through said chamber, and adjustable means for admitting outside air to the gaseous mixture issuing from said chamber. 80
9. In a vaporizing device of the character described, a vaporizing chamber consisting of a plurality of superimposed relatively long, narrow and shallow sections, a supply of liquid in front of said chamber, an impeller wheel partly submerged in said liquid, atomizing and directing said liquid to said sections, by centrifugal action, means for redirecting to said liquid supply liquid unvaporized within said chamber, a suction fan at the delivery end of said chamber, a shaft carrying both said impeller wheel and fan, adjustable means for admitting outside air to the suction end of said fan and for regulating the flow of gas thereto from said chamber. 85
10. In a vaporizing device of the character described, a vaporizing chamber consisting of a plurality of superimposed relatively long, narrow and shallow sections, a supply of liquid in front of said chamber, an impeller wheel partly submerged in said liquid, atomizing and directing said liquid to said sections, by centrifugal action, means for redirecting to said liquid supply liquid unvaporized within said chamber, a suction fan at the delivery end of said chamber, a shaft carrying both said impeller wheel and fan, and adjustable means for admitting outside air to the suction end of said fan and for regulating the flow of gas thereto from said chamber. 90
11. In a vaporizing device of the character described, a vaporizing chamber consisting of a plurality of superimposed relatively long, narrow and shallow sections, a supply of liquid in front of said chamber, an impeller wheel partly submerged in said liquid, atomizing and directing said liquid to said sections, by centrifugal action, means for redirecting to said liquid supply liquid unvaporized within said chamber, a suction fan at the delivery end of said chamber, a shaft carrying both said impeller wheel and fan, adjustable means for admitting outside air to the suction end of said fan and for regulating the flow of gas thereto from said chamber. 95
12. In a vaporizing device of the character described, a vaporizing chamber of cellular formation having a plurality of vertically spaced substantially horizontal substantially imperforate partitions, each adapted to collect and retain liquid spread in a thin film, said partitions forming a plurality of relatively long narrow passages providing relatively long paths of travel for said liquid and also providing a relatively large evaporating surface, means for projecting liquid into said passages, means directing a current of air through said passages, and means for preheating said air. 100
